[57] **CLAIM**

The ornamental design for a folding garden tool, as shown and described.

DESCRIPTION

FIG. 1 is a front elevational view of a folding garden tool in a partially open position showing my new design;

FIG. 2 is a front elevational view of the folding garden tool in its closed position;

FIG. 3 is a side elevational view thereof;

FIG. 4 is a rear elevational view thereof;

FIG. 5 is a top plan view thereof; and

FIG. 6 is a bottom plan view thereof.

*Fig. 1.**Fig. 5.**Fig. 2.**Fig. 3.**Fig. 4.**Fig. 6.*
